BOX PLATE

James Johnson, Saco, Maine, assignor to Draper Corporation, Hopedale, Mass., a corporation of Maine

Application November 9, 1939, Serial No. 303,629

5 Claims. (Cl. 139—183)

The present invention pertains to shuttle boxes for fly shuttle looms and more particularly relates to front box plates for such shuttle boxes.

The usual shuttle box of the type mentioned 5 comprises front and back box plates fixed to a loom lay, each box plate comprising an elongated body having a shuttle guiding surface. The shuttle guiding surface of the front box plate commonly consists of a flexible lining, such as 10 leather, fixed to one side face of the box plate. The leather lining commonly extends forwardly across the inner or entrance end of the box plate. The shuttle box is of proper width, forwardly and rearwardly of the loom, to grip and thereby 15 check the shuttle when the latter is properly directed. The shuttle box is, however, so narrow that a forwardly mis-directed shuttle will not enter the box but will strike the inner end of the front box plate.

20 The usual loom shuttle is provided with a steel tip which must be kept reasonably sharp. It is found that under certain weaving conditions, particularly with high speed looms, the shuttle is frequently mis-directed in a forward direction far enough that the sharp steel tip of the shuttle 25 will strike the inner end of the front box plate. If the lining of the front box plate extends forwardly across the said inner end, the point of the shuttle makes holes in the lining and soon 30 renders it unfit for service. In many instances, the lining must be removed and replaced solely because of this damage by the shuttle tip, the lining being otherwise still in good condition. The omission of the forwardly extending part 35 of the lining prevents said damage to the lining, but is even more objectionable because the shuttle tip is then damaged by striking the metal body of the box plate. A rigid, and particularly a metal guard or cover for the lining would be 40 similarly objectionable.

A principal object of the present invention is to provide a front box plate for fly shuttle looms as aforesaid, which box plate shall have a yielding, non-metallic cushion fixed thereto and extending across the inner end thereof, to receive 45 and cushion the impact of a forwardly mis-directed shuttle, to thereby effectively prevent the box plate or shuttle tip from being damaged when the shuttle strikes the inner end of the box plate.

The foregoing and other objects of the invention are accomplished in the construction illustrated on the accompanying drawing, of which:

55 Fig. 1 is a plan view of a loom shuttle box

having the preferred embodiment of my improved front box plate applied thereto; and

Fig. 2 is a perspective view of the inner end portion of said preferred front box plate.

The drawing shows only a shuttle and the right hand end of a loom lay with a shuttle box including my improved front box plate, the rest of the loom being of any suitable usual construction forming no part of the present invention. The lay includes a lay beam 1 which is mounted on swords, of which right hand sword 2 is shown, for reciprocation toward and from the front of the loom. The front of the loom is toward the bottom of the drawing on Fig. 1. A fly shuttle 3 is picked from side to side of the loom, along the lay beam 1, by any suitable mechanism including a picker stick 4. The ends of the shuttle are tapered as indicated at 5 and are each provided with a sharp steel tip 6 as is usual. The lay has a shuttle box at each end thereof, of which only the right hand shuttle box is shown. This shuttle box includes a back box plate 7 which has its inner end fastened to the sword 2 at 8 and its outer end fastened to the lay beam at 9. The back box plate 7 has a shuttle guiding surface 10 which is positioned in a vertical plane extending longitudinally of the lay and shuttle box.

The shuttle box shown also includes a front box plate. This box plate comprises an elongated metallic body 11, commonly of cast iron, which is adapted to be attached to the loom lay. To this end, the body 11 may have an ear 12 having a slot 13 for receiving a screw 14 for attaching the inner end of the box plate to the lay. The outer end of the body 11 may have a slot 15 for receiving a similar attaching screw 16. The body 11 has a longitudinal shuttle guiding surface on one side face thereof. As shown, this surface comprises a strip 17 of flexible material, preferably leather, lining the rear face of the body 11. The lining strip is stretched taut and cemented or otherwise secured to the body 11. The inner end of the strip 17 extends forwardly at 18 across the inner end 19 of the front box plate.

45 The box plates are so positioned that the respective shuttle guiding surfaces 10 and 17 are spaced apart just far enough to properly receive the shuttle 5 when the latter properly enters 50 the shuttle box. However, it often happens that the shuttle 5 is so improperly thrown that the tip thereof will be directed well forward of the longitudinal center line of the shuttle box. In fact, the shuttle is at times mis-directed, forwardly, 55

to the extent that the tip 6 strikes the inner end of the front box plate, thereby damaging the forwardly extending part 18 of the lining 17. The present invention provides means for effectively preventing this damage to the lining 17.

In accordance with the present invention, damage to the part 18 of lining 17, or to the shuttle tip 6 if such part should be omitted, is prevented by means of a cushion which is fastened to and extends across the inner end of the body 11. The particular cushion shown comprises a resilient pad 20, preferably of non-metallic material such as rubber, and a flexible cover 21 therefor. The pad 20 is of substantial thickness at its rearward end 22 and this end portion is rounded horizontally as shown. The cover 21 is made of a strip of non-metallic material, preferably of a fibrous nature such as leather. This strip is folded intermediate its ends to provide two vertical portions. The pad 20 is positioned between the vertical folds of the cover 21. The forward end of the cushion thus formed is fixed to the inner end of the body 11 in any suitable manner, as by rivets 23, and the rearward end of the cushion is preferably left free.

The cushion just described extends entirely across the inner end of the body 11 and completely covers the forwardly extending part 18 of the lining, so that a forwardly mis-directed shuttle will strike the cushion and can not strike any other part of the inner end of the front box plate. The cover 21 being non-metallic, it can not damage the shuttle tip 6. Neither is the cushion objectionably damaged by the shuttle tip, because the resilient pad 20 yields to absorb the impact of the shuttle and thereby prevents the shuttle tip 6 from penetrating the cover 21 to an objectionable depth. This action of the cushion takes place when the shuttle tip 6 strikes the cushion squarely. The rearward end of the cushion is positioned in longitudinal alignment with the shuttle guiding surface 17 and, as above noted, is rounded and is free to yield. The result is that if the shuttle is only slightly mis-directed as shown by Fig. 1 it will be cammed or guided rearwardly and therefore may become properly boxed in the shuttle box. The yielding cushion is found to be much more effective in deflecting a slightly mis-directed shuttle than was the rigid rounded inner end of prior front box plates.

Having fully disclosed the preferred embodiment of my invention, I claim:

1. A front box plate for the shuttle box of a fly shuttle loom, said box plate comprising an elongated body having means whereby it is adapted to be attached to a loom lay, said body having a longitudinal shuttle guiding surface on one side face thereof, and a resilient cushion fixed to the inner end of said body and extending across said end with its rearward end positioned

in substantial longitudinal alignment with the shuttle guiding surface of said box plate, whereby said cushion receives the impact of a forwardly misdirected shuttle.

2. A front box plate for the shuttle box of a fly shuttle loom, said box plate comprising an elongated metal body adapted to be attached to a loom lay, said body having a longitudinal shuttle guiding surface on one side face thereof, and a cushion fixed to the inner end of said body and extending across said end in position to receive the impact of a forwardly mis-directed shuttle, said cushion comprising a resilient pad positioned within a folded strip of flexible, non-metallic material.

3. A front box plate for the shuttle box of a fly shuttle loom, said box plate comprising an elongated metal body adapted to be attached to a loom lay, said body having a shuttle-engaging lining comprising a strip of flexible material fixed on one side face of the body and extending forwardly across the inner end thereof, and a cushion fixed to said inner end of said body and covering the forwardly extending portion of said lining, said cushion comprising a pad of non-metallic resilient material positioned between vertical folds of a strip of flexible fibrous material, whereby said cushion is adapted to receive the impact of a forwardly mis-directed shuttle.

4. A front box plate for the shuttle box of a fly shuttle loom, said box plate comprising an elongated metal body adapted to be attached to a loom lay, said body having a longitudinal shuttle guiding surface on one side face thereof, and a resilient, non-metallic cushion extending across the inner end of said body, the forward part of said cushion being fixed to said body and the rearward part thereof being free to yield under the impact of a forwardly mis-directed shuttle, the rearward end of said cushion being horizontally rounded and terminating substantially in longitudinal alignment with said shuttle guiding surface.

5. A front box plate for the shuttle box of a fly shuttle loom, said box plate comprising an elongated metal body adapted to be attached to a loom lay, said body having a shuttle-engaging lining comprising a leather strip fixed along one side face of the body and extending forwardly across the inner end of the body, and a cushion fixed to said inner end of said body and covering the forwardly extending part of said lining to protect the latter against damage by a forwardly mis-directed shuttle, said cushion comprising a pad of resilient rubber material positioned between vertical folds of a leather strip, the rearward end of said cushion being horizontally rounded to deflect a slightly mis-directed shuttle rearwardly.

JAMES JOHNSON.
